Patented Nov. 4, 1919.

UNITED STATES PATENT OFFICE.

HEINRICH V. P. NIELSEN, OF BOSTON, MASSACHUSETTS.

MOLD FOR USE IN BUILDING WALLS.

1,320,791.

Specification of Letters Patent.

Patented Nov. 4, 1919.

Application filed February 12, 1917. Serial No. 147,999.

To all whom it may concern:

Be it known that I, HEINRICH V. P. NIELSEN, a citizen of the United States, residing at Boston, in the county of Suffolk and State 5 of Massachusetts, have invented certain new and useful Improvements in Molds for Use in Building Walls, of which the following is a specification.

My invention relates to the art of constructing walls from plastic material, particularly cement walls, and it has for its object to make it possible to erect a wall of the character described with accuracy and despatch and to provide simple and efficient 15 means for use in constructing the same.

To these ends my invention consists, first, of the improved means for use in constructing walls from cement and the like and second, in the novel method employed in 20 constructing a wall of this kind in accordance with my invention, all as set forth in the following description and particularly pointed out and defined in the claims at the close thereof.

25 In the accompanying drawings:

Figure 1 is a perspective view of a partially constructed wall showing my new apparatus applied thereto.

Fig. 2 is a plan view of a portion of the 30 apparatus shown in Fig. 1.

Fig. 3 is a section on line 3—3 of Fig. 2.

Fig. 4 is a perspective view of one of the transverse ties hereinafter described.

Having reference to the drawings W, W' 35 represent the upper portion of a partially built cement wall having an air space w between the two sections W W' of the wall. Incorporated in each section W of the wall is a plurality of upright reinforcing rods or 40 bars w' arranged in pairs and a plurality of ties w² through each of which extend two of the rods w'.

The wall is built in courses with the aid of one or more molds each comprising essentially two outside walls 1 and 1^a each of 45 which is provided at its top edge with dowels or studs 3 and at its bottom edge with a corresponding number of dowels or studs 4 each arranged immediately below one of the 50 dowels 3. These dowels 3 and 4 are preferably the ends of flat metal bars 5 fastened by screws or otherwise to the inner sides of the walls 1 and 1^a.

In starting to build a wall the two walls 55 1 and 1^a of the mold are placed on edge upon

the ground with a tie w² applied to each pair of dowels or studs 4 at the bottom of the mold, said ties resting on the ground. Each tie w² is provided near each end with a hole or perforation w³ to receive the dowels 60 or studs 4 and, between said holes w³, with two other holes w⁴ each adapted to receive an upright reinforce rod w⁵. After the dowels or studs 4 have been engaged with the several ties w² that are placed under the 65 walls 1 and 1^a a corresponding number of ties w² are slipped down over the upright reinforce rods w⁵ and lowered thereon until they are engaged with the dowels or studs 3 at the upper edges of the side walls 1 and 70 1^a. It will thus be clear that the ties w² serve as rigid connections between the top edges of the side walls 1 and 1^a and the bottom edges thereof. In order, however, to prevent sidewise displacement or movement of the 75 side walls 1 and 1^a and hold them rigidly upright, each of said walls is provided upon its outer side with two pairs of straps 6, one pair near each end, and each pair adapted to receive a post 7 which may be made from 80 wood.

When the first or bottom course of the wall is being cast the posts 7 may be driven into the ground but on the other courses wedges 8 will be driven into position between the lower ends of said posts and the course to the top of which the mold is applied. With the posts 7 properly in position the side walls 1 and 1^a of the mold and the reinforce bars w' are held in proper upright 90 positions.

The mold herein shown is adapted to produce a wall comprising the two sections W and W' separated by the air space w and for this reason it is made to include a partition 95 9 provided at its top edge with dowels or studs 10 spaced the same as the dowels 3, and at its bottom edge with dowels or studs 11 spaced the same as the dowels 4. Also each tie w² is made at its middle with a 100 third dowel perforation w³, the middle perforations w³ of the ties under the mold receiving the dowels 11 and the middle perforations w³ of the ties w² on top of the mold receiving the dowels 10.

The ends of the mold are closed by end walls 12 each provided at its upper and lower ends with dowels 13 engaging ties w² above and below the side walls and partition 105 of the mold.

After assembling the parts of the mold and the reinforcing elements of the wall the cement is deposited in the chambers between the side walls and partition tamped firmly 5 down into place.

After the cement within the mold sets the ties w^2 on top of the latter are slid upwardly on the reinforce rods w' far enough to disengage them from the dowels at the top of 10 the mold and then the parts of the latter are removed, after which the ties that were lifted are lowered into position on the freshly cast wall and are later used to receive the dowels 4 and 11 of the mold when 15 the latter is re-assembled on the wall to cast the next course above.

It will thus be seen that the important feature of my mold is that its parts are held in proper relative position by the ties w^2 , 20 that the mold holds the topmost set of ties in the positions they are to occupy in the wall and that these mold holding ties become incorporated in the wall and serve as transverse binders and reinforcing members, as 25 well as a means for coupling the lower edges of the walls of the mold to the top of the wall being constructed.

The perforated ends of the ties w^2 being near the exterior of the wall under construction 30 are accessible so that they can be used as anchorages for supporting a staging if desired.

My improved mold is of simple and inexpensive construction and by its aid unskilled

workmen can rapidly erect a wall of cement 35 or the like.

In the accompanying drawings I have shown my improved mold as angular in shape so as to be used in casting the portions of the two walls adjacent a corner at 40 which they meet but, obviously the mold may be made of any desired shape.

What I claim is:

1. A molding outfit of the character described comprising a single pair of vertical 45 side wall members; two sets of ties, one set for connecting the upper portions of said side wall members and the other set for connecting the lower portions of said side wall members, and studs on said side wall members immediately adjacent the upper and lower edges thereof for separably engaging with the ends of said ties.

2. A molding outfit of the character described comprising a single pair of vertical 55 side wall members; two sets of ties, one set for connecting the upper portions of said side wall members and the other set for connecting the lower portions of said side wall members; studs on said side wall members 60 immediately adjacent the upper and lower edges thereof for separably engaging with the ends of said ties, and end walls for closing the ends of the mold.

In testimony whereof I have affixed my 65 signature.

HEINRICH V. P. NIELSEN.

Copies of this patent may be obtained for five cents each, by addressing the "Commissioner of Patents, Washington, D. C."
